US00D936668S

(12) United States Design Patent (10) Patent No.: US D936,668 S
Smith et al. (45) Date of Patent: * Nov. 23, 2021

(54) DISPLAY SCREEN OR PORTION THEREOF
WITH A GRAPHICAL USER INTERFACE

(71) Applicant: HULU, LLC, Santa Monica, CA (US)

(72) Inventors: Hansen Smith, Los Angeles, CA (US);
John Couch, Topanga, CA (US); Josh
Nelson, Los Angeles, CA (US); Linda
Sum, Santa Margarita, CA (US)

(73) Assignee: HULU, LLC, Santa Monica, CA (US)

() Term: 15 Years

(21) Appl. No.: 29/708,813

(22) Filed: Oct. 9, 2019

Related U.S. Application Data

(62) Division of application No. 29/589,983, filed on Jan. 5, 2017, now Pat. No. Des. 872,732.

OTHER PUBLICATIONS

Co-Pending Design U.S. Appl. No. 29/589,983, filed Jan. 5, 2017, with same title.

Primary Examiner — Daniel J Domino

(74) Attorney, Agent, or Firm — Fountainhead Law Group, P.C.

(57) CLAIM

We claim the ornamental design for a display screen or portion thereof with a graphical user interface, substantially as shown and described.

DESCRIPTION

The FIGURE is a front view of a display screen or portion thereof with a graphical user interface showing our new design.

The outermost broken line shows an environment, whereas the remaining broken lines show a display screen and elements of a graphical user interface. None of the broken lines form part of the claimed design.
